GAME APPARATUS

Filed Feb. 21, 1927

UNITED STATES PATENT OFFICE.

KEITH J. EVANS, OF CHICAGO, ILLINOIS.

GAME APPARATUS.

Application filed February 21, 1927. Serial No. 169,794.

My invention relates to improvements in game apparatus and consists of the following features and advantages.

An object of the invention is to provide an apparatus for playing a game similar to the well known game of basket ball, but by use of which the game may be played in the home without any danger of damage being wrought by contact of the ball or balloon with pieces of furniture and the like.

A further object of the invention is to provide a game apparatus of extreme compactness in form when the game is not in use. This feature greatly facilitates the shipping and handling of the apparatus prior to use.

A further object of the invention is to provide in a game apparatus a balloon constructed of a single piece of soft rubber, and representing a basket ball, in which novel means is employed for maintaining the neck or air port of the balloon within the bounds of the external surface of the balloon when inflated.

A further object of the invention is to provide in a game apparatus novel means for substantially rigidly supporting the loop or basket member in a horizontal plane during the use of the game.

Other objects and advantages of my invention will appear more fully from the following description and from the accompanying drawings in which similar characters of reference indicate similar parts throughout the several views.

In the drawings, Fig. 1 is a perspective view of the game apparatus set up and in use.

Fig. 2 is a sectional view along the line 40 2—2 of Fig. 1.

Figs. 3, 4 and 5 are sectional views through a portion of the balloon, illustrating the means for confining the neck within the bounds of the external surface of the balloon.

In carrying out my invention I make use of a rectangular cardboard box 1, having shallow side walls 2. I also provide a cover for the box, which is not shown, for use when the various parts of the apparatus are confined within the box, as in transporting the game and during such times as the game is not in use.

The apparatus so confined within the box consists in a loop corresponding to the basket used in basket ball, as shown at 3, hav-

ing a twisted neck portion 4 formed by twisting the adjacent ends of the wire forming the loop, and diverging legs 5 at the outer portion of the twisted neck 4, the legs 60 5 each terminating in an eyelet 6. This loop or basket member, when still within the box 1, lies in a single plane. The 90 degree bend at the inner end of the neck, as shown at 7, is not formed until such time as the game 65 is to be set up for use.

A plurality of rubber balloons, one of which is shown at 8, rubber bands 9, and gummed stickers 10 are also confined within the box.

The means for fixing the loop or basket to the box 1 consists in three strands of picture wire 11, and three metal washers 12, which are employed in the manner hereinafter described.

The first step in setting up the apparatus is that of bending the loop or basket, as shown at 7, the length of the twisted portion 4 being about $2\frac{1}{4}$ inches. The box 1 is then turned with its bottom surface 13 outwardly, and the loop is secured to the bottom surface of the box by projecting picture wire 11 through holes 14 punched through the bottom wall of the box. The picture wire 11 encompasses the base of the diverging legs 5, is projected through the adjacent hole 14, through a washer 12, and is twisted so as to prevent the withdrawal of the wire there-through. In like manner the other two strands of picture wire are passed through the eyes 6 and through adjacent holes 14 and washers 12, and secured by twisting the wire at the rear of the washer.

The loop or basket is now held on a horizontal plane and substantially rigid.

It will be noted that the box 1 performs a double function, that of confining the parts when the game is not in use, and that of supplying a substantially rigid support. This latter feature is due to the integral side walls 2 of the box. The box is supported in any well known manner upon the wall, at a height determinable by the age or size of the players.

First the balloons are inflated by blowing air through their neck portions 15. When the balloon has been inflated to a diameter slightly less than the diameter of the loop 3, the rubber band 9 is tightly wound about the neck 15 so as to confine the air within the balloon.

The neck 15 is then protruded manually

into the adjacent yielding surface of the balloon, as shown in Fig. 4, and a gummed sticker 10 is secured to the surrounding surfaces of the balloon and there held until the adhesive material of the sticker dries sufficiently to hold the sticker in place.

I have thus provided a balloon of a single piece of material which when inflated does not possess any external protruding portions or members, which might prevent free movement of the balloon through the loop.

In use, any one of several rules may be carried out, corresponding to the rules employed in basket ball, with the exception that no player is allowed to hold or advance the ball. The ball may be projected above the loop and permitted to drop through, or it may be projected up through the loop.

I claim—

1. Game apparatus comprising a shallow box having a substantially flat bottom wall, a wire loop having a radially extending neck and diverging leg portions at the outer end of the neck, said loop when in use having its neck portion bent at an angle of ninety de-

grees at the outermost end thereof, means for securing the diverging legs securely to the bottom wall of the box, and an inflated balloon for projection through the loop, said box being of sufficient size to confine all of the parts of the apparatus, including the wire loop, prior to the bending of its neck as described.

2. A game apparatus comprising a shallow box having a substantially flat bottom wall, a circular loop having a radially extending neck with portions of the neck constructed for attachment to the external bottom wall of the box, said loop when in use having its neck portion bent at an angle of 90 degrees at that end adjacent to the loop and an inflatable balloon for projection when inflated through said loop, said box being of such contour as to confine all of the parts of the apparatus when not in use including the loop prior to the bending of its neck.

In witness whereof, I hereunto subscribe my name this 19th day of February, 1927.

KEITH J. EVANS.
